(57) **CLAIM**

The ornamental design for a multiple blade adjustable knife, as shown and described.

DESCRIPTION

FIG. 1 is a perspective view of a multiple blade adjustable knife showing my design;

FIG. 2 is a first side view thereof;

FIG. 3 is a second side view thereof, opposite that shown in FIG. 2;

FIG. 4 is a top view thereof;

FIG. 5 is a bottom view thereof;

FIG. 6 is a front view thereof;

FIG. 7 is a back view thereof; and,

FIG. 8 is an environmental view illustrating an expanded view of the multiple blade adjustable knife of FIG. 1 positioned in hand of a subject.

The broken lines in the drawings illustrate portions of the multiple blade adjustable knife that form no part of the presently claimed design.
